UNITED STATES PATENT OFFICE.

JOHN M. HANSEN, OF PITTSBURG, PENNSYLVANIA.

GONDOLA CAR.

SPECIFICATION forming part of Letters Patent No. 727,622, dated May 12, 1903.

Application filed August 11, 1902. Serial No. 119,244. (No model.)

To all whom it may concern:

Be it known that I, JOHN M. HANSEN, a resident of Pittsburg, in the county of Allegheny and State of Pennsylvania, have invented a new and useful Improvement in Gondola Cars; and I do hereby declare the following to be a full, clear, and exact description thereof.

My invention relates to railway-cars, and more especially to gondola cars having a metal underframe and wooden floor and sides.

The object of the invention is to improve cars of this description, in the details hereinafter described and claimed.

In the accompanying drawings, Figure 1 is a side view of one half of the car. Fig. 2 is a longitudinal section of the other half of the car, said section being taken partly on the longitudinal center of the car and partly on a plane between the center and side sills. Fig. 3 is a plan view of the underframing of one half of the car. Fig. 4 is an end view of the car. Fig. 5 is a transverse section, the left-hand portion being taken on the line 5-5, Fig. 3, and the right-hand portion on the line 25 5^a-5^a, Fig. 3. Fig. 6 is a longitudinal vertical section, on an enlarged scale, through one of the hoppers. Fig. 7 is a transverse section through the same. Fig. 8 is a plan view of a portion of one of the hoppers on an enlarged 30 scale. Fig. 9 is a detail view of the brake-shaft support. Fig. 10 is a detail side view of the anchor for the safety-chain eyebolt, and Fig. 11 is a plan view of the same.

The underframe comprises longitudinal 35 sills, end sills, draft-sills, body-bolsters, diaphragms, and suitable connecting means therefor. The longitudinal sills are channel-shaped sections of the built-up-girder type. There are four longitudinal sills—two center 40 sills 1 and two side sills 2,—each comprising a top angle-bar 3, a bottom angle-bar 4, and a connecting web-plate 5, the latter being of varying depth, greatest at its center section and tapering thence toward the body-bolsters. 45 The two center sills are also provided at their lower edges with angle-bars 6, located on the side opposite the angle-bars 4. The body-bolsters 7 comprise web portions 8, of general channel form, one located on either side 50 of the center sills and extending thence outwardly to the side sills. Two such channel shapes are placed back to back and are suit-

ably united to the center sills and are further connected by means of a top cover-plate 9 and a bottom cover-plate 10, which cover-plates are riveted to the top and bottom flanges, respectively, of the channel shapes and extend uninterruptedly the one above and the other below the center sills. The channel-shaped web members 8 are of the same depth as the longitudinal sills and preferably are deeper at their inner ends than at their outer ends, the center sills at the body-bolsters being shown as of greater depth than the side sills. Between the center sills in line with the web portions 8, is the center brace 11, formed, preferably, of a casting, suitably secured to the center sills and provided with a boss 12, which has a vertical opening for receiving the king-pin. Side 70 bearings 13 are riveted to the lower cover-plate 10, and the center plate will also be riveted to said cover-plate.

The end sills 15 are of general channel shape in cross-section and of varying depth, being deepest at the center of the car and tapering thence to the sides thereof. Their outer ends are preferably closed or boxed in and receive the ends of the side sills 2, to which they are suitably riveted, the corners being reinforced by means of the push-pole pockets 16 and corner connecting or gusset plates 17. To the latter are riveted the outer ends of diagonal angle-braces 18, the inner ends of which are riveted to gusset or connecting plates 19, suitably secured to the center sills and body-bolster. The center sills project somewhat beyond the body-bolster, and the draft-sills 20 are secured to said projecting ends and have their outer ends fitting in the channel end 90 sill and suitably secured thereto by means of angle-pieces 21. These draft-sills are of channel-shaped cross-section, of less depth than the center sills, and each has its upper flange cut away at the inner end, so that the web can overlap the end of a center sill and be riveted thereto. Suitable draft-lugs, coupler-horn braces, draw-bar carriers, and the like are provided.

The underframe is tied together at intervals by means of shallow diaphragms 24, composed of sections of channel-bar which are united to the side and center sills by means of angle-pieces 25. These diaphragms have

their upper faces located somewhat below the level of the longitudinal sills and form supports for the wooden floor-stringers 26. The wooden floor 27 rests directly upon these wooden floor-stringers, the top cover-plate of the body-bolster, and a top cover-plate 28, secured to the center sills.

The sides of the car 29 are formed of planks and are supported at intervals by suitable trough-shaped stakes 30 and angle-bar stakes 31. The ends 32 of the car are hinged, so that they can drop. Near the center of the car are four pockets or hoppers symmetrically disposed about the center of the car. The bottoms of these pockets are sealed by means of drop-doors 35, which when closed lie in a horizontal position. On the transverse sides of the pockets or openings next to the transverse center line of the car are comparatively deep channel-shaped diaphragms 36, which are secured to the center and side sills by means of the angle-pieces 37. To the bottom and top flanges of these diaphragms are attached bars 38, which pass continuously one above and the other below the center sills. To these diaphragms are secured hinge-lugs 39, on which the doors 35 are hinged. On the transverse sides of the openings, parallel to the diaphragms 36, are shallower Z-shaped diaphragms 40, which form the opposite wall of the pocket. The lower flanges of these Z-shaped diaphragms project inwardly with reference to the pocket and form door-stops, while to the diaphragms 36 are riveted angle-bars 41, which form door-stops on that side. The walls of the pocket, which extend longitudinally of the car, are formed of angle-shaped members 42, having top flanges which project outwardly with respect to the pockets and rest on top of the longitudinal sills. These members are also provided with end flanges 43, which abut against the webs of the transverse diaphragms and are riveted thereto. To these members are riveted angle-bars 44, which serve as door-stops. The doors are raised and lowered and held in position by means of chains 45 passing over guide-sheaves 46 and connected to a winding-shaft 47. This arrangement of hoppers or pockets above the doors in cars with wooden floors is very desirable. Heretofore such pockets have had their walls composed of wooden members or of wooden and metal members, and frequently they have not been completely sealed when the cars were built, or if completely sealed originally the shrinkage of the timber members has caused openings to develop in time through which some of the lading could escape. My invention precludes the possibility of such trouble.

The brake-shaft 50 has its lower end stepped in the support or step 51, the latter being formed from a section of flanged bar, preferably an angle-bar, which is bent on a large curve, as shown in Fig. 9, with the two portions thereof at right angles, the vertical member being riveted to the end sill and the hori-

zontal member serving as the support or step for the brake-shaft. The projecting flange of the angle-bar is cut away, as at 52, and is entirely removed for a portion of the length of the bar, and the other flange or web is then bent backward upon itself, as at 53, to form a portion of double thickness, which serves as the support for the lower end of the brake-shaft.

At each end of the car I provide two safety-chains, one on either side of the draw-bar. One of said chains is provided at its extremity with a link and the other with a hook, the arrangement being such that when two cars are coupled there is always a hook on one car opposite a link on the adjacent end of the next car. Each safety-chain is secured to the end sill by means of an eyebolt 55, which passes through the end sill and through a suitable anchor 56, secured on the inner face thereof. This anchor is of general angle shape and is preferably formed of a casting having a hub 57, through which the shank of the eyebolt passes. The anchor is provided with a vertical flange 58, which is riveted to the end sill, and horizontal flanges 59, which are riveted to the horizontal flange of an angle-piece 60, the vertical flange of which is riveted to the end sill. This angle-piece 60 lies underneath the anchor and projects a considerable distance at both sides thereof and serves to distribute the stress on the eyebolt over a relatively large area on the end sill.

What I claim as my invention, and desire to secure by Letters Patent, is—

1. In a car, the combination with the underframing and floor, of a pocket or hopper formed in said floor, a drop-door for closing said pocket or hopper, the walls of said pocket or hopper being formed by suitable flanged transverse diaphragms secured to the longitudinal sills of the underframe, and suitable flanged side members interposed between said diaphragms and secured thereto, said members having top flanges resting on the longitudinal sills, the side members and diaphragms forming a metallic rectangular box above the door and below the level of the floor.

2. In a car, the combination with the underframing and floor, of a suitable pocket or hopper in said floor, a transverse diaphragm of flanged shape forming one of the walls of said diaphragm, the upper flange of said diaphragm serving as a support for the floor and the lower flange serving as a door-stop, a diaphragm arranged parallel thereto, and two longitudinal angle-shaped side hopper-plates having their flanges resting on the longitudinal sills and provided at their ends with flanges which are riveted at the corners to the diaphragms, thus forming a rectangular metallic box.

3. In a car, the combination with the underframe and floor, of a pocket or hopper in said floor, a transverse Z-shaped diaphragm forming one of the walls of said pocket and hav-

ing its lower flange projecting inwardly and serving as a door-stop, a channel-shaped transverse diaphragm parallel thereto, two angle-shaped side hopper-plates lying between said transverse diaphragms and secured thereto and having their flanges resting on the longitudinal sills, angle-bars riveted to said plates and to the channel-shaped diaphragm and serving as door-stops, and a horizontal door hinged to one of said transverse diaphragms.

4. A brake-shaft support comprising a section of flanged metal bent to form a substantially right-angled body with a flange extending along the vertical member and beyond the bend, the vertical member of said support being adapted to be secured to the end sill and the horizontal member being provided with a bearing for the lower end of the

25 brake-shaft.

5. A brake-shaft support consisting of a flanged piece of metal bent to form a substantially right-angled body, the projecting flange of the horizontal member being cut 25 away at the end and the web bent back upon

itself to form a portion of double thickness, and a bearing for the brake-shaft formed in said thickened portion.

6. A safety-chain anchor for railway-cars comprising an angle-shaped bracket adapted for attachment to the inner face of the end sill and having an integral boss or hub provided with a hole to receive the shank of the safety-chain eyebolt.

7. In a railway-car, the combination with the end sill, of an angle-shaped metallic member secured to the inner face thereof with its horizontal flange projecting inwardly, a safety-chain anchor secured to said angle member and provided with an integral boss or hub having a hole therethrough, and a safety-chain eyebolt projecting through the end sill and secured in said hub or boss.

In testimony whereof I, the said JOHN M. HANSEN, have hereunto set my hand.

JOHN M. HANSEN.
